UNITED STATES PATENT OFFICE.

WARREN C. ROCKWELL, OF MOUNT CARMEL, ASSIGNOR TO HIMSELF AND
LUDLUM B. ROCKWELL AND FRANCIS S. ROCKWELL, OF SUNBURY, PA.

TIN-ROOF CLEAT.

SPECIFICATION forming part of Letters Patent No. 331,655, dated December 1, 1885.

Application filed May 7, 1885. Serial No. 164,716. (No model.)

To all whom it may concern:

Be it known that I, WARREN C. ROCKWELL, a citizen of the United States, residing at Mount Carmel, in the county of Northumberland and State of Pennsylvania, have invented 5 a new and useful Improvement in Tin-Roof Cleats, of which the following is a description.

Figure 1 shows a side view of the roof-cleat. Fig. 2 represents a section of roof transversely to the seams, showing on the left the first step and on the right the second step of securing the plates. Fig. 3 is an enlarged section showing the final bending and completion of the seam.

15 The object of my invention is to provide a means for more securely anchoring or tying a tin or other sheet-metal roof down to the sheathing, and which will permit of the convenient and expeditious application of the sheets forming the roof in a cheap and simple manner.

It consists in a cleat formed of a flat piece 20 of sheet metal having a square staple incorporated in a bend of its lower end, and whose upper end is adapted to be folded and fastened in the bending operation in the seam, as will be hereinafter fully described.

In the drawings, A represents the sheet-metal portion of the cleat, and B is the square staple, whose middle portion is contained in a bend of the lower portion of the sheet metal A. The shanks of the staple are preferably twisted or barbed to give them greater holding-power in the wooden sheathing, and the sheet-metal part of the cleat is preferably made widest at the top, and is slit longitudinally.

25 In laying a roof with this cleat the unfinished edge X of roofing has the upturned flange a, against which is to be fitted the upturned flange a' of the next strip of tin, A'. Before applying this strip of tin A', however, the cleat is secured to the sheathing by driving 30 its staple into the sheathing parallel with and close up against the standing flange a of the unfinished roof-section, with the sheet-metal part A projecting above and lying flat against the said flange a. The next strip A' of 35 tin is then laid with its flange a' flat against

the flange a of the strip previously laid, leaving the cleat between, as shown on the left of Fig. 2. Now one of the slotted ends, c, of the cleat is bent over one flange, a, and the other slotted end, c', is bent over the other flange, a', 55 as shown on the right of Fig. 2, and the seamer then turns the whole into two or more folds in the usual manner, leaving the rib or seam as shown completed at C in Fig. 3, in which the slotted ends of the cleat are thoroughly 60 anchored, while the staple firmly holds the same down to the sheathing.

A great advantage that the staple has over the nails which have heretofore been driven through the cleat into the sheathing is, first, 65 that the staple does not pierce the sheet metal, but has a broad bearing against it in the bend which holds it tightly down to the sheathing and does not allow it to work loose from the wind. When nails are driven through the 70 sheet-metal cleats, they tear holes through it and leave lines of fracture, and as the head of the nail has but little bearing the working of the roof up and down from the wind is apt to work the nail-holes larger than the heads, 75 and eventually they possess no holding-power, the wind passing under the roof tears it off.

I am aware that the standing seam of a roof has been fastened down by a staple on the outside that straddled the seam and 80 pierced the roof; but in this case the extra expense is incurred of soldering around each of the prongs of the thousands of staples in a roof, and at best the roof is apt to be leaky.

The cleats, as formed of the sheet-metal 85 section with the staple attached, are designed to be furnished to the trade ready made, and, while being greatly superior to the old forms of fastening, they are also cheap and save a great deal of bother and annoyance in cutting 90 the cleats.

As a modification of my invention, I may make the sheet-metal part A of the cleat in two pieces of equal size, folded at their lower ends around the staple and folded reversely 95 at the top.

Having thus described my invention, what I claim as new is—

1. A cleat for sheet-metal roof-seams, consisting of a staple having a square or right- 100

angular middle portion and a sheet-metal strip having one end folded around said staple, substantially as described.

2. A cleat for sheet-metal roof-seams, consisting of a staple having a square or right-
5 angular middle part and a sheet-metal strip, having one end folded around the middle part of the staple and the other end made wider and slitted, as described.

10 3. A sheet-metal roof consisting of strips of sheet metal having upturned adjacent flanges combined with a sheet-metal cleat arranged between the upturned flanges and folded therewith into a seam, the said cleat having
15 its lower end folded around a square staple arranged below the roof and driven into the

sheathing, substantially as and for the purpose described.

4. A sheet-metal roof consisting of strips of sheet metal having upturned adjacent flanges 20 combined with a sheet-metal cleat made widest at its upper end and slitted and bent in reverse direction over the flanges, and a staple folded in the lower end beneath the roof and driven into the sheathing, the said 25 cleat and sheet-metal flanges being turned over to form a seam, as described.

WARREN C. ROCKWELL.
